UNITED STATES PATENT OFFICE.

JOHN D. PLANCHAMP, OF CHICAGO, ILLINOIS.

DESIGN FOR A WATCH-CASE.

SPECIFICATION forming part of Design No. 16,605, dated April 6, 1886.

Application filed October 24, 1885. Serial No. 180,876. Term of patent 7 years.

To all whom it may concern:

Be it known that I, JOHN D. PLANCHAMP, a citizen of the United States, residing at Chicago, in the county of Cook and State of Illinois, have invented a certain new and original Design for Watch - Cases, which is fully set forth in the following specification, reference being to the accompanying drawing, forming a part hereof, and in which—
5 The drawing shows the side view of a watch-case formed according to my design.
10 The peculiarity of my design consists in forming at the ends of the box joints of the style of case known as "Louis XIV," having
15 heads looking in opposite directions from the ends of such box-joint, which, by means of the

peculiar construction of such style of case, can be made to conform gracefully with the circumference of the case and form an artistic and very pleasing design.

20

What I claim is—

A design for a watch-case, the same consisting of a case provided with box-joints at the hinge, and stem ornamented upon each of the ends thereof, with heads looking in opposite 25 directions, substantially as shown and described.

JOHN D. PLANCHAMP.
